UNITED STATES PATENT OFFICE.

ELLSWORTH GRAY, OF HUMBLE, TEXAS.

SPEAR.

1,414,511.

Specification of Letters Patent. Patented May 2, 1922.

Application filed April 14, 1921. Serial No. 461,363.

To all whom it may concern:

Be it known that I, ELLSWORTH GRAY, a citizen of the United States, residing at Humble, in the county of Harris and State 5 of Texas, have invented certain new and useful Improvements in a Spear, of which the following is a specification.

This invention relates to certain new and useful improvements in a spear.

10 One object of the invention is to provide a device of the character described specially designed for use in with-drawing pipe which may become stuck in a well bore.

15 Another object is to provide a spear which may be readily let down into a well bore and which will enter the pipe to be pulled and engage therewith to withdraw the same, and also embodies means whereby it may be easily released from the pipe 20 and withdrawn in case the pipe cannot be pulled.

A further feature resides in the provision of a spear which is adapted for use either in deep or shallow wells.

25 With the above and other objects in view this invention has particular relation to certain novel features of construction, operation and arrangement of parts, an example of which is given in this specification and 30 illustrated in the accompanying drawings, wherein:—

Figure 1 is a vertical sectional view of the spear, and

Figure 2 is a transverse sectional view 35 taken on the line 2—2 of Figure 1.

Referring now more particularly to the drawings, the numeral 1 designates the pipe to be pulled. The numeral 2 designates an actuating shaft which has a central annular 40 rib 3. The upper section of this shaft has right hand threads and the lower section has left hand threads. Threaded onto the upper end of the shaft 2 there is a coupling 4 into which the lower end of the string 45 of pipe 5 is threaded. This string is used to let the spear down into, and withdraw it from the well bore.

Threaded onto the upper right-hand-threaded section of the shaft there is a nut 50 6 formed with a lateral lug 7. Fitted over the shaft 2 beneath the coupling 4 there is a tubular jaw 8 having a vertical slot 9 in one side in which the lug 7 runs. The inner contour of the jaw flares downwardly 55 and its periphery has annular engaging

teeth 10. Threaded onto the lower or left-hand-threaded section of the shaft 2 there is a sleeve 11, frusto-conical in general contour, over which the sleeve fits, and whose upper end abuts against the rib 3 when 60 the sleeve is screwed home. The extreme lower end of the shaft 2 is reduced and has right-hand threads to receive the pointed head 12 adapted to be screwed thereon. The shaft 2 and head 12 have connecting water 65 courses to permit the passage of water downwardly therethrough. The lower end of the sleeve is recessed to receive the head 12, forming the annular shoulder 13, against which said head is adapted to abut.

In operation the spear is let down into the bore and the pointed head will direct it into the pipe to be pulled. The jaw is of a size to fit closely within said pipe and when an upward pull is exerted on the string 70 5 the teeth 10 will engage with said pipe and the jaw will be spread by the upwardly tapering sleeve and held in secure engagement with the pipe and the pipe thus withdrawn. In case the pipe is too tightly struck to be pulled it becomes necessary to release and withdraw the spear. The spear may be released by rotating the string in a right-hand, or clockwise, direction. When so rotated the nut 6 will be run up against the 75 annular inwardly extending flange 14 carried by the upper end of the jaw, and the sleeve will be run downwardly until the shoulder 13 thereof abuts against the head 12 and a continued rotation of the string and shaft, 2 will cause the nut 6 to elevate the jaw and release it from the wedging effect of said sleeve and it will be thereby released from the pipe and may be withdrawn.

What I claim is:—

1. A spear including an actuating shaft, a string to the lower end of which said shaft is attached, the upper and lower sections of said shaft being reversely threaded, a nut threaded onto the upper threaded section, an expansible jaw fitted over said shaft and nut and whose upper end has an inwardly extending shoulder, means for preventing the relative rotation of said nut and jaw, a tapering sleeve threaded onto the lower threaded section of said shaft and adapted to wedge between said shaft and jaw to expand the latter, and a head carried by the lower end of the shaft.

2. A spear including an actuating shaft,

a string to the lower end of which said shaft is attached, the upper and lower sections of said shaft being reversely threaded, a nut threaded onto the upper threaded section, an expansible jaw fitted over said shaft and nut and whose upper end has an inwardly extending shoulder, means for preventing the relative rotation of said nut and jaw, a tapering sleeve threaded onto the lower threaded section of said shaft and adapted to wedge between said shaft and jaw to expand the latter, and a head carried by the lower end of the shaft, said shaft, when rotated, operating to carry said sleeve against said head and also to carry said nut against said shoulder, whereby the jaw is withdrawn from the sleeve.

3. A spear including an actuating shaft having upper and lower sections, reversely threaded, an expansible jaw fitted over said shaft, a tapering sleeve threaded onto the lower section and adapted to wedge between the shaft and jaw to expand the latter, means adapted to be actuated by the upper section of said shaft into engagement with said jaw, said shaft, when rotated, operating to force the sleeve away from said jaw and acting through said means to release said jaw from said sleeve.

4. A spear including an actuating shaft having upper and lower sections, reversely threaded, an expansible jaw fitted over said shaft, a tapering sleeve threaded onto the lower section and adapted to wedge between the shaft and jaw to expand the latter, means adapted to be actuated by the upper section of said shaft into engagement with said jaw, said shaft, when rotated, operating to force the sleeve away from said jaw and acting through said means to release

said jaw from said sleeve, and means for rotating the shaft.

5. A spear including an actuating shaft whose upper and lower sections are reversely threaded, an upwardly tapering sleeve screwed onto the lower section, a nut threaded onto the upper section, a downwardly tapering expansible jaw fitted loosely over said shaft and nut and whose lower end is formed to receive the sleeve, said nut and sleeve being moved apart when the shaft is rotated in one direction and being moved toward each other when the shaft is rotated in the opposite direction, a head carried by the lower end of the shaft which limits the downward movement of the sleeve on the shaft and a shoulder carried by said jaw, against which the nut is adapted to engage to release the jaw from said sleeve.

6. A spear including a shaft having reversely threaded upper and lower sections, a nut threaded onto the upper section, a lateral lug carried by the nut, a downwardly flared expansible jaw fitted over the shaft and nut and having a vertical slot in one side, into which the lug projects, an inwardly extending annular flange carried by the upper end of the jaw, against which the nut is adapted to abut, an upwardly tapering sleeve threaded onto the lower section of the shaft and formed to enter and expand said jaw, and a head carried by the lower end of the shaft.

In testimony whereof I have signed my name to this specification in the presence of two subscribing witnesses,

ELLSWORTH GRAY.
